JOHN M. GITCHELL, OF HAVERHILL, ASSIGNOR TO J. F. MORSE,
OF NORTH HAVERHILL, NEW HAMPSHIRE.

Letters Patent No. 83,151, dated October 20, 1868.

IMPROVEMENT IN SEED-PLANTERS.

The Schedule referred to in these Letters Patent and making part of the same.

To all persons to whom these presents may come:

Be it known that I, JOHN M. GITCHELL, of Haverhill, in the county of Grafton, and State of New Hampshire, have invented a new and useful Improvement in Corn or Seed-Planters; and do hereby declare the same to be fully described in the following specification, and represented in the accompanying drawings, of which—

Figure 1 is a top view,

Figure 2 a bottom view, and

Figure 3 a longitudinal section of a planter, as provided with my invention.

This planter, like many others in use, has not only a hopper, A, to receive the seed, but a furrow-opener, B, and two coverers, C C, they being arranged in a frame, D, in manner as represented. Such frame is provided with two handles, E E.

The bottom of the hopper is a slide-plate, F, which has an opening, a, leading down through it. This opening is supplied with an adjustable gauge-plate, b, which is provided with a screw, c, by which it may be moved, so as to close the said opening more or less. A brush, d, is also arranged in the front of the lower part of the hopper. In order that access may be easily had to the screw, it is arranged outside of the hopper, as shown in fig. 3.

There is pivoted to the hopper a vibratory frame, G, which supports the shaft e of a wheel or roller, H, arranged just in rear of the coverers. A gang of pulleys, f g h, on the shaft of the said roller or wheel, disposed with respect to another gang, i k l, in manner as shown in the drawings, is to impart rotary motion to the latter, by means of an endless band or chain working around one pulley of each of the two gangs.

The gang i k l is fixed on a shaft, m, which has a bell-crank, n, at its middle, and extends across and is pivoted in the frame G. A pitman or connecting-rod, o, is jointed to the said bell-crank and to the rear end of the slide-plate F. Consequently, while the machine may be dragged along by a draught-animal, harnessed to the nose-piece p of its frame, the slider will have reciprocating rectilinear motions imparted to it through the action of the wheel H, the endless belt or chain, the pulleys, (on which the belt or chain may be working,) the cranked shaft, and pitman or connecting-rod, as described.

The wheel H will not only perform the functions of rolling down the earth which the coverers may have replaced in the furrow, but will aid in producing the movements of the slide-plate necessary to effect the dropping of the seed from the hopper.

By means of the vertically-vibrating frame G, supporting the crank and wheel-shafts, the wheel is enabled to bear on and accommodate itself to the surface of the ground, the pitman rising and falling with the frame.

I therefore claim, for effecting the reciprocating movements of the slider F, by means of the wheel or roller H, the combination of the vibratory frame G, the pulleys, the cranked shaft, and the pitman, arranged with the slider, the wheel-shaft, and the hopper, in manner, and to operate with an endless band or chain, substantially as specified.

JOHN M. GITCHELL.
